UNITED STATES PATENT OFFICE.

GEORGE W. LANCASTER, OF RICHMOND, VIRGINIA.

DEVICE FOR AUTOMATICALLY STOPPING TRAINS.

No. 892,270.

Specification of Letters Patent.

Patented June 30, 1908.

Application filed February 25, 1907. Serial No. 359,164.

To all whom it may concern:

Be it known that I, GEORGE W. LANCASTER, a citizen of the United States, residing at Richmond, in the county of Henrico and State of Virginia, have invented certain new and useful Improvements in Devices for Automatically Stopping Trains; and I do hereby declare the following to be a full, clear, and exact description of the invention, such as will enable others skilled in the art to which it appertains to make and use the same.

This invention relates to a device for automatically stopping trains and particularly to trips located along the tracks at predetermined distances and means secured to a train and adapted to come in contact with the trip and be operated thereby.

The invention comprises the production of a trip mechanism that is to be thrown into or out of operation by the same mechanism that operates the ordinary signals and semaphores and means connected therewith mounted upon the train for placing on the brakes of the train.

The object in view is the production of a trip mechanism positioned along the track and means mounted on a train and adapted to be operated for throwing on the brakes of the train when the trip mechanism is in operative position.

Another object in view is a trip mechanism mounted near the track and means mounted on the train, adapted to be operated by the trip mechanism for throwing the brakes on and means for operating said mechanism when the semaphores are operated.

With these and other objects in view the invention comprises certain other novel constructions, combinations and arrangements of parts as will be hereinafter more fully described and claimed.

In the accompanying drawings:—Figure 1 is a side elevation of a trip mechanism and means operated thereby carried by the train, formed according to the present invention. Fig. 2 is a perspective view of a trip mechanism formed according to the present invention, showing a semaphore connected therewith. Fig. 3 is a perspective view of a trip mechanism forming part of the present invention in its lowered or inoperative position together with a semaphore and connecting mechanism, the semaphore being shown at caution. Fig. 4 is a perspective view of a tripping mechanism showing it in its lowered or inoperative position, and a semaphore at

safety being shown in connection therewith. Fig. 5 is a section of Fig. 4 on line 5—5. Fig. 6 is a side elevation of a tripping mechanism constructed according to the present invention and a slightly modified form of means secured to the train that is adapted to be operated by the trip. Fig. 7 is a top plan view of an engineer's valve and connecting mechanism. Fig. 8 is a slightly modified form of means connecting the semaphore with the tripping mechanism. Fig. 9 is a cross sectional view through a track having secured thereto a modified form of my invention. Fig. 10 is a cross section through a track having a slightly modified form of the tripping mechanism mounted thereon, and a car and mechanism secured thereto adapted to be operated by the tripping mechanism. Fig. 11 is a side elevation of the tripping mechanism shown in Fig. 9 together with mechanism secured to a train that is adapted to be operated by the trip as the train passes thereover. Fig. 12 is an enlarged detail side elevation of a modified form of tripping mechanism. Fig. 13 is a valve mechanism secured to the train. Fig. 14 is a side elevation of the valve mechanism shown in Fig. 13. Fig. 15 is a bottom plan view of the valve mechanism shown in Fig. 13. Fig. 16 is a detail, sectional view through part of a semaphore showing locked means therefor.

In block signal systems it has been customary to operate semaphores at predetermined distances along the entire system of tracks and provide therefore mechanism that the cars will operate for automatically throwing to danger the semaphores in case the block ahead is occupied.

The present invention is adapted to be applied either to automatically or manually operative systems with equal advantage. In the description herewith of the present invention the term semaphore is intended to mean a semaphore that may be either operated manually or automatically.

Referring more particularly to the drawings 1 indicates the rails of a track and 2 a semaphore arm. The present invention is designed to be used in connection with a semaphore that is adapted to have the arm 2 locked in position when thrown to danger so that the mechanism connected with the semaphore cannot be accidentally moved to safety without unlocking the semaphore. Any desired locking means may be used, but

I preferably use the locking mechanism shown in Fig. 16. Referring more particularly to said figure, shaft 3 is pivotally mounted and is adapted to rotate the semaphore arm 2. Rigidly secured to shaft 3 in any preferred way is a sleeve 4 formed with a projection 5, which is adapted to engage a notch or groove 6 formed in a locking member 7. The locking member 7 is pivoted at 8 in any convenient way and provided at the opposite end with an armature 9 which is adapted to be attracted by magnet 10. When the semaphore arm 2 is at danger a current of electricity keeps energized magnet 10, which in turn holds armature 9 in contact therewith. This will hold the locking means 7 against the sleeve 4, thus causing lug 5 to engage notch 6. From this it will be observed that shaft 3 carrying arm 2 cannot rotate until magnet 10 has been deprived of its current. When the train, in case of the automatic system, or the switchman in case of the tower system deprives the magnet 10 of current, the locking member is dropped to the dotted position shown in Fig. 16. By this it would be evident that when the locking member 7 is in this position the lug 5 will be disengaged from slot 6 and will permit arm 2 to be moved either to safety or to caution.

Connected to shaft 3 Fig. 2 is a sprocket 11 which is adapted to carry a chain 12. Chain 12 engages at the lower end a sprocket 13 which has secured thereto a disk 14. Disk 14 operates substantially as a crank, and if desirable a crank may be substituted therefor as may be evident. Secured to disks 14 at 15 is a link 16 which is adapted to reach from pivot point 15 to a crank 17. Link 16 is pivoted at 18 to crank 17 so as to partially rotate shaft 19 which is rigidly secured to crank 17. It will be observed from Fig. 2 that when link 16 is at a dead center with respect to disk 14 that crank 17 is off the center so as to permit shaft 19 to be rotated upon movement of link 16. When the semaphore is moved for raising arm 2 to caution, pivot point 15 will be rotated to the position shown in Fig. 3 and when arm 2 is thrown into a safety position pivot point 15 will be rotated to the position shown in Fig. 4. It will be observed that disk 14 only makes a partial rotation and that arm 2 passes danger in order to reach safety or caution.

Connected to shaft 19 or formed integral therewith are crank members 20-20. The arms or crank members 20-20 are provided with stub shafts or pins 21-21 for operating in slots 22-22 formed in the pivotally mounted members or arms 23-23. The members or arms 23-23 are pivotally mounted on shaft 24 and have formed on the outer end thereon lugs or extensions 25-25 that move in an arc of a circle struck from the center of a shaft 24. The movement of lugs 25-25 is comparatively short and consequently their movement is sub-

stantially a reciprocating movement, that is, a movement for raising them above rails 1 and again lowering them to said rails. Stub shafts 21-21 are adapted to move in slots 22-22 of the arms or pivotal members 23-23 for raising and lowering the outer end of the lugs 25-25. As the shaft 19 does not rotate entirely around, but gives only a back and forth or oscillatory movement, the arms or cranks 20-20 are simply moved the distance of a quadrant by the reciprocating movement of the link 16. When the arm 2 is in a danger position as seen in Fig. 2 the shaft 19 is oscillated or rocked so as to move cranks 20-20 to their upper or danger position as clearly seen in Fig. 1. When in this position the lugs 25-25 are in their uppermost or operative position, and are adapted to operate a valve 26 secured to the engine of a train passing thereover. If desired the valve 26 may be placed upon any of the cars of the train without departing from the spirit of the present invention. Valve 26 is connected to the main air pipe which in turn is connected to the air brakes of the train so that when arm 27 of valve 26 strikes lug 25, valve 26 will be opened and air will be permitted to escape from the air brake system and consequently apply the brakes. When the valve 26 has been opened for permitting the escape of the air from the brakes it will remain open until manually closed. From this it will be evident that when the lever or arm 27 is rotated by lug 25 and valve 26 is opened the brakes will be applied and the main air pipe of the brake system will be held open. As long as the valve 26 is open the brakes will not be released as it will be impossible to apply the air brakes on account of the open valve 26. In order to release the brakes it will be necessary to close valve 26 and then permit the mechanism on the engine to fill the brake cylinders in the usual way. After the brakes are thus released the train may proceed or not as circumstances may dictate. Whether the train proceeds or remains stationary after the brakes have been applied and then released will not affect in the least the position of the tripping arm or pivotally mounted members 23-23. These arms or members together with the projection 25 will remain up until the semaphore arm 2 has been thrown to safety or caution. The throwing of the arm 2 to caution or safety is accomplished by automatic mechanism when the track is clear or by manually operative means in any usual or well known way, the same not forming a part of the present invention.

In the drawings the trip or pivotally mounted members 23 are shown as being placed on each side of the rails but it will be evident that the same may be placed between the rails. I have also shown a plurality of tripping mechanisms 23-23, but it will be

evident that one mechanism could be used. The use of two tripping members simply allows the valve 26 to be placed in a certain position upon all of the engines that are designed to pass over the rails 1 so that the lever 27 connected to valve 26 will be operated regardless of the direction of the engine. If one trip were used the same would be placed centerly of the track for engaging the lever 27 as the same passes thereover.

As shown in Fig. 1 a valve of any preferred construction may be used, but I preferably use a valve constructed as shown in Figs. 13, 14 and 15. Referring more particularly to Figs. 13, 14 and 15, 28 indicates the pipe leading to the main air pipe. Pipe 28 is screw-threaded at 29 and has placed thereon a cap 30. Cap 30 has formed thereon a threaded offset portion 31 which is designed to receive a second cap 32. Cap 30 is formed with a bottom 33 which is provided with an aperture 34. Pivotally mounted in cap 32 is a member 35 constructed somewhat in the manner of a shutter and is adapted to rotate in cap 32. The shutter or rotating disk 35 is provided with an aperture 36 formed similar to aperture 34. An arm 37 is formed integral with or rigidly secured to disk 35. The arm 37 is adapted to project through a slot 38 in cap 32 and move back and forth therein. The arm or bar 37 is adapted to rotate disk 35 so as to make aperture 36 register with aperture 34 for permitting air to escape from pipe 29. When this form of valve is used it is placed similarly to valve 26, but preferably has pipe 28 extending directly to main air pipe 39. Suitable braces of any preferred kind may be used to hold the pipe 28 in position when the engine passes over lug 25 and arm 37 strikes lug 25. As the engine continues to move the disk 35 will be rotated sufficiently to cause apertures 34 and 36 to register. This will open the air pipe 39 and set the brakes.

In Fig. 8 will be seen a slightly modified form of means for connecting the semaphore with shaft 19. Instead of using sprocket wheel 11 and chain 12 and connecting mechanism a crank 40 is rigidly secured to the shaft 3 of the semaphore to the outer end of which is pivoted a link 41. It will be observed that when arm 2 is moved link 41 will be reciprocated and consequently will oscillate shaft 19.

In Figs. 6 and 7 will be seen a slightly modified form of mechanism for applying the air brakes. Referring more particularly to the figures just mentioned, 42 is the engineer's valve for controlling the brakes and 43 is a lever for controlling the valve 42. Secured to the lever 43 or formed integral therewith is a segmental rack 44. A gear 45 meshes with rack 44 and has secured thereto a shaft 46 which is held in position in bearings 47 and 48. Bar or shaft 46 is formed at its

lower end with an arm 49 and in operative position. The same is placed at a substantially right angle to the main portion of the bar so as to contact with lug 25 when the same is raised to danger. When the engine carrying valve 42 and shaft 46 and surrounding mechanism passes lug 25 arm 49 comes in contact therewith and will be moved thereby. The movement of arm 49 will partially rotate shaft 46 which in turn will rotate gear 45 and move rack 44 and lever 43. It will be observed that in its operative position arm 41 is positioned at right angles to the track so as to engage lug 25 as the train passes over the track and arm 49 will engage lug 25 when same is raised and if not raised arm 49 will remain in operative position with valve 42 closed and brake of train unapplied. When lug 25 is raised and arm 49 and shaft 46 are rotated lever 43 is partially rotated and opens valve 42 which apply the brakes of the train. After the brakes have been applied the engineer may release them by simply revolving lever 43 back to its normal position and this will close valve 42 and allow the air pump of the engine to refill the brake cylinders.

Referring more particularly to Figs. 9, 10, 11 and 12 there will be seen a slightly modified form of the tripping mechanism. Referring more particularly to the modification just mentioned 50 is a trip pivotally mounted to a supporting member 51. Trip 50 is provided with a contact member 52 and a rack 53 which is adapted to engage a gear 54. Gear 54 is secured to a shaft 55 which is adapted to be operated by a gear 56 engaging rack 57 which in turn is operated by a semaphore 58. The semaphore 58 is of any usual or preferred construction but pivoted with a sprocket wheel 59 for moving a chain 60 which has secured to its lower ends a pivotally mounted bar 61. Bar 61 is pivotally mounted at 62 so that when chain 60 is propelled by the sprocket 59 bar 61 will be oscillated and in turn reciprocate rod or link 63 that is connected to rack 57. A clamp 60' surrounds and grips a shaft 61' to which arm 58 is rigidly secured. Clamp 60' has secured thereto in any desire way, as, for instance, by clamping between the parts thereof, a depending arm 62' that is provided with a weight 63'. Weight 63' acting through arm 62' will give the semaphore arm 58 a continuous tendency to remain at the danger position and will only be removed therefrom when properly unlocked and operated. The semaphore 58 may be provided with locking means of any preferred construction, but I preferably employ locking means as shown in Fig. 16. It will be observed that semaphore 58 is locked when at danger, but not locked when at caution or at safety. When the semaphore 58 is moved it will communicate motion to trip 50, but when the arm of the semaphore 50 is at danger it will be

locked and the track member 52 will also be locked. I have shown only one trip 50, but it will be evident that more than one may be used and that the position of the same will be varied according to the various circumstances as may be necessary. Trip 52 is adapted to engage an arm 37 as shown in Figs. 10 and 11. When arm 37 engages trip 50 it will be rotated and cause apertures 34 and 36 to register. This will permit the air to escape from the brake system which will in turn permit the brakes to be applied. The trip member 52 is rigidly held in a vertical position when semaphore 58 is at danger by reason that semaphore 58 is locked when at danger and consequently trip 50 and mechanism connecting the same with the semaphore will be held against movement. This will prevent arm 37 from forcing trip member 52 into a lowered position rather than being rotated thereby. It will be observed that when semaphore 58 is at danger that track member 52 is in a vertical position and that when semaphore 58 is at safety contact member 50 is on a substantially horizontal plane on one side of shaft 55 and is moved to a substantially horizontal plane on the opposite side of shaft 55 when the semaphore 58 is moved to caution.

30 By the use of trips formed according to the present invention connected to the various semaphores positioned along the track and operated by the same mechanism that operates the semaphores, means are provided that will automatically stop the train whether the engineer sees the signals or not. It will be observed that the trip mechanism is operated at the same time as the signals or semaphores and by mechanism connected thereto. This obviates the necessity of putting in new systems and various means for operating the trips as the train passes over the track. Where the system of automatic signals thrown to caution and danger in the face of the train is used the present invention is adapted to work with great advantage. The automatic moving of the various signals to danger will also at the same time automatically move the trip mechanism in a position for operating the brakes of the train as the same passes the signals.

The present invention is designed preferably to be used upon a system where the trains as they move over the track will automatically throw the signals to danger in case of obstructions ahead so that when the semaphore is thrown to danger by the automatic means already used on the system, the present invention will be operated thereby.

60 When the present invention is used upon a system which will automatically throw to danger the semaphore upon the approach of the train, it will, upon the semaphore going to danger, be automatically set into opera-

tive position for stopping the train so that 65 not only is there a visual signal for the engineer, but means for positively stopping the train even against the wishes of the engineer.

What I claim is:—

1. A device of the character described 70 comprising pivotally mounted trips, means for partially rotating said trips, means operated by a semaphore for moving said trip rotating means, and longitudinally operated means for locking said trips in operative position, said means comprising a lug projecting from said rotating member, a rotating member, a gripping member formed with a notch partially encircling said rotating member, said lug being adapted to engage said 80 notch, an electric magnet, and means controlled by said semaphore for causing said lug to engage said notch.

2. In a device of the character described, a trip, means rotated by the movement of a 85 semaphore for raising and lowering said trip, means mounted on a train adapted to be operated for applying brakes to said train, said means comprising a tube connected with the air brake pipes, a cap removably secured to 90 said pipes and formed with an opening therein, a disk-shaped member pivotally secured to the end of said cap and adapted to normally close the opening in said cap, said disk-shaped member being formed with an aperture for registering with the opening of said cap, a handle for engaging said trip and adapted to be moved and thereby moving said disk-shaped member for bringing the opening formed therein in registry with the 100 opening formed in said cap, and an auxiliary cap removably secured to said first mentioned cap and arranged to hold said disk-shaped member against the end of said first mentioned cap, said second mentioned cap being 105 formed with a slot for accommodating the movement of said handle.

3. A device of the character described, comprising trips, mechanism designed to engage said trips mounted upon a car, air brake 110 valves operated by said mechanism, a semaphore for operating the said trips and a lock for locking said semaphore at danger, said lock comprising a pivotally mounted member formed with a notch therein, a sleeve 115 and catch secured to said sleeve and adapted to engage said notch, and an electrical magnet designed to move said pivotally mounted member for bringing said notch into engagement with said catch when said semaphore 120 is thrown to danger.

In testimony whereof I affix my signature in presence of two witnesses.

GEORGE W. LANCASTER.
